UNITED STATES PATENT OFFICE

WILLIAM P. DE SAUSSURE, JR., OF ENGLEWOOD, NEW JERSEY, ASSIGNOR TO DE SAUSSURE EQUIPMENT COMPANY, OF WEST NEW YORK, NEW JERSEY, A CORPORATION OF DELAWARE

TABLE

Application filed October 10, 1931. Serial No. 588,046.

This invention relates to tables, particularly tables of the type in which the table top may be readily connected and disconnected from the support therefor.

One of the principal objects of the invention is to provide a simple, cheap, strong and rigid form of table.

Another object is to provide a simple strong form of table support separable from the table top and provided with legs which may be folded together when not in use so as to occupy a minimum of space.

A further object of the invention is to provide a base for a table top and a table support formed substantially wholly of standard structural shapes and sheet material.

Two suitable forms of construction are shown, by way of example, in the accompanying drawings, wherein:—

Fig. 1 is a side elevation of one form of the table as a whole;

Fig. 2 is a section on the line 2—2 of Fig. 1;

Fig. 3 is a plan view of the base of the table top taken on the line 3—3 of Fig. 2;

Fig. 4 is a perspective view of the base of the table top;

Fig. 5 is a plan view of the upper part of the table support taken on the line 5—5 of Fig. 2;

Fig. 6 is a perspective view of the table support with the legs removed;

Fig. 7 is a perspective view of the locking bolt support;

Fig. 8 is a longitudinal central section through the locking bolt;

Fig. 9 is a section on the line 9—9 of Fig. 8;

Fig. 10 is a plan view of a modified form of table top base;

Fig. 11 is a section on the line 11—11 of Fig. 10;

Fig. 12 is a plan view of the upper part of a modified form of table support (with the legs removed) suitable for use with the table top base shown in Fig. 10;

Fig. 13 is a section on the line 13—13 of Fig. 12; and

Fig. 14 is a vertical section on the line 13—13 of Fig. 12 through the table top base and support therefor in assembled relation.

Referring to the drawings, and first to Figs. 1 to 9, the table comprises a table top 10, a base 11 therefor, a table support formed of a top 12 and four legs 13 pivotally connected thereto. The base 11 comprises a square plate 14 to which are spot-welded one flange of each of four short angles 15, arranged so that each angle is perpendicular to the angles adjacent thereto.

To the upstanding flange of each angle is spot-welded a flange of one of four long angle bars 16 so that the angles 15 and the angle bars 16 together form members having two parallel horizontal flanges and an intervening vertical flange or web. The angles 15 and angle bars 16 are so arranged that the inner ends of the latter form the four walls of a square central space or chamber 17 at the middle of the plate 14. As shown in Fig. 1, the angle bars extend outwardly nearly to the edge of the table top 10 and are secured to the latter at intervals by any suitable means, such as rivets 18.

The table support comprises a top 12 formed of four sections of sheet metal bent into U-form and each having a long arm 19 and a short arm 20. The end of each short arm is bent outwardly to form a flange 21, which is secured by spot-welding to the outer side of the long arm of the adjacent U. In this way an interlocking structure is obtained in the form of a hollow cross with a central square chamber and four rectangular pockets 22 extending radially from the four sides of the central chamber but separated therefrom by vertical partitions.

The long arm of each U butts against the inner side of the long arm of the adjacent U. To further lock these parts together, a cap 26 is employed, formed of a square plate, with its corners turned over, as shown in Fig. 7, and spot-welded to the outer faces of the arms 19. This plate is centrally apertured to permit the insertion of the welding tool.

Various means may be employed for detachably connecting together the base 11 and top 12. Most desirably, and as shown, a nut and bolt type connection is provided. A nut 25 having square sides adapted to fit in the

chamber 17 in the base 11 is inserted therein and held in place by spot-welding it to the walls of the chamber.

A bolt 27 having a square head is arranged 5 with its head within the central chamber in the top 12 and held in place by two caps 24 spot-welded to the inner walls of such chamber. The upper cap 24 and the plate 14 are centrally apertured to allow the threaded end 10 of the bolt to extend upwardly through such apertures and enter the nut 25. It is convenient to make both caps 24 of identical construction and hence the lower cap 24 is likewise apertured. Each of these caps is formed 15 of a single stamping. Spacers 23 are inserted between the lower cap 24 and the cap 26. These spacers are to advantage made of channel cross-section and of such size that when placed in abutting relation, as shown in 20 Fig. 7, they will exactly fit within the central chamber formed by the four arms 19. The outer faces of the spacers 23, 23 may then be attached by spot-welding to the contacting 25 inner faces of the arms 19, so as to aid in the locking together of the latter. The table top 10 and its base 11 may be attached and detached from the top 12 of the table support by turning the former so as to screw or unscrew the nut 25 onto or off the bolt 27.

30 A cheap and convenient form of bolt construction is shown in Figs. 8 and 9. The body of the bolt is made from round bar stock threaded at one end. The other end is turned down to form a cylindrical shank 40 of uniform diameter with a shoulder 41. A series of square-sided washers 42 are slipped over this shank 40 and held in place by upsetting the projecting portion of the shank at 43. These washers are prevented from turning 35 on the shank by milling a flat on one side of the shank and forming the aperture in the washers with a complementary flat portion. The rectangular chamber which receives the caps 24 and the head of the bolt 27 need not be of any standard size to enable the washers to be formed from strip material of standard width. The washers may be made from strips narrower than the internal width of such caps provided that they are cut to a 40 length equal to such width and are threaded on the shank 40 in staggered relation, as shown in Figs. 8 and 9.

The four radially arranged pockets 22 in the top 12 are designed to receive the upper 45 ends of the legs 13. The latter are to advantage formed of rectangular metallic tubing. The upper ends of the legs are pivotally attached to the top 12 by pins 29. Outward movement of the legs is limited by engagement of the latter with bottom edges 30 of the top 12, as shown in Fig. 2. These edges are preferably beveled to increase the bearing surfaces in contact with the legs.

While it is desirable to have the legs 50 ranged so that when the table is disassembled

the legs may be folded together, it is not desirable to have the legs free to move inward should the table be lifted. The table is, therefore, constructed so that the act of connecting the table top to the support therefor automatically clamps or locks the legs in outwardly extended or splayed position. This is accomplished in the construction shown by cutting the tops of the legs so that their upper surface is flush with the upper surface of the top 12 when the legs are in outwardly extended position. With the legs so formed, inward movement of the legs involves raising the tops of the latter above the upper edges of the U members of the top 12 and this is impossible when the plate 14 is clamped down on the top 12 by the action of the nut 25 and the bolt 27.

The bottom of each leg may be closed by a bent strip of metal 44 spot-welded in place.

The form of construction shown in Figs. 10 to 14, inclusive, differs from that shown in Figs. 1 to 9, inclusive, chiefly in the manner in which the base of the table top is connected to the upper part of the table support. In the form of construction above described, the connection is of the nut and bolt type. In the modification of Figs. 10 to 14, the connection is made by a snap lock.

The base for the table top in such modification comprises a circular plate 14a, to the upper surface of which is spot-welded one flange of each of four short angles 15a. To the upstanding flange of each angle is spot-welded a flange of one of four long angle bars 16a. The angles 15a and angle bars 16a are so arranged as to leave a central space at the center of the plate 14a.

The table support comprises a top 12a formed of four sections of sheet metal bent 55 into U-form and, each having a long arm 19a, and a short arm 20a, assembled as described in connection with the corresponding parts of Figs. 1 to 9, inclusive. These parts are spot-welded together as in the construction of Figs. 1 to 9, and are further locked together by members 23a of sheet metal. At the upper end of the central square chamber and resting on the upper edges of the members 23a is a split centrally apertured cap 37. Between the two halves of this cap a boss 32 is arranged, this boss having an annular groove into which the inner edges of the two halves of the cap extend to lock the boss 32 in position. After assembly the parts of the cap are spot-welded to the arms 19a. The plate 14a is formed 110 with a central aperture 33 having a diameter equal to that of the base of the boss 32, so that when the base of the table top is placed on the upper part of the table support the two parts are held in concentric relation to each other. The boss 32 has a tapered top to facilitate the insertion of the boss into the aperture 33.

115

120

125

130

To the inner face of the central web 34 of each U-shaped member is welded a rigid plate 35 with an inturned flange 36 at its upper end. The underside of this flange is spaced above the top of the cap 37 a distance equal to the combined thicknesses of the plates 14a and 31. The distance between the inner edges of diametrically opposite flanges 36 is somewhat greater than the diameter of the plate 14a, so that the latter can be passed downwards between the flanges. Welded to the top of the plate 14a are four equally spaced plates 31, arranged with their ends projecting sufficiently beyond the periphery of the plate 14a to engage the underside of the flanges 36, as shown in Fig. 14, when the table top and its base have been turned clockwise through the requisite angle with respect to the top 12a of the table support.

To retain the ends of the plates 31 in engagement with the flanges 36, a spring strip 38 is attached at its lower end to the inner face of one of the central webs 34. The upper part of this spring strip is bent inwardly so that when the end of one of the plates 31 has been forced over it by the above mentioned clockwise movement, this strip will spring back behind the plate 31 and hold the table base and table support in locked position. It will be noted that the depending flanges of the angle bars 16a extend below the tops of the plates 35, their flanges 36 and spring strip 38, so that clockwise movement of the table top beyond that required to force one of the plates 31 past the spring strip 38 is prevented by such flanges. The table top can, therefore, only be detached by turning it in an anti-clockwise direction.

The corners of the projecting ends of the plates 31 are beveled so as to allow the latter to be forced past the end of the spring strip 38 in either direction. As, however, the force required to accomplish this movement is greater than any force applied to the table in the course of ordinary use, the table top is firmly held in position by such spring strip until it is desired to disassemble the table.

In the form of construction last described, outward movement of the legs 13 prior to engagement of the table top with the table support is limited by engagement of the inner edges of the leg tops with the inner walls of the radial pockets in the top 12a. At no time do the sides of the legs engage the lower margins of the central webs 34, as in the form shown in Figs. 1 to 9, inclusive. After the table top has been brought into engagement with the table support, the legs are held in correct angular position by engagement of their beveled upper ends with the underside of the plate 14a.

What is claimed is:

1. A table support, comprising a member having at least three pockets disposed radially and symmetrically about the vertical

axis of the support, each pocket being formed of sheet metal bent about vertical lines of fold into U-form, a leg mounted between the arms of each U, and means for attaching said member to a table top.

2. A table, comprising a table top, a support therefor, means for detachably connecting said top and support, a plurality of legs pivotally connected to said support, the upper ends of said legs projecting above the top of said support when the legs are drawn together, whereby the connection of said top to said support causes the table top to engage the upper ends of the legs and hold the latter in outwardly splayed, table-supporting position.

3. A table support, comprising a member having at least three pockets disposed radially and symmetrically about the vertical axis of the support, each pocket being formed of sheet metal bent about vertical lines of fold into U-form, a leg pivoted between the arms of each U, a stop for limiting outward pivotal movement of each leg, and means for attaching said member to a table top.

4. A table support, comprising a member having at least three pockets disposed radially and symmetrically about the vertical axis of the support, each pocket being formed of sheet metal bent about vertical lines of fold into U-form, a leg pivoted between the arms of each U, outward pivotal movement of each leg being limited by engagement of the central portion of the U with the outer part of the leg, and means for attaching said member to a table top.

5. A table support, comprising a member having four pockets disposed radially and symmetrically about the vertical axis of the support, each pocket being formed of sheet metal bent about vertical lines of fold into U-form, with one arm longer than the other, the end of the short arm being connected to the outer side of the long arm of one adjacent U and the end of the long arm being connected to the inner side of the long arm of the other adjacent U to form an interlocking structure, a leg pivoted between the arms of each U, and means for attaching said member to a table top.

6. A table support, comprising a member having four pockets disposed radially and symmetrically about the vertical axis of the support, each pocket being formed of sheet metal bent about vertical lines of fold into U-form, with one arm longer than the other, the end of the short arm being connected to the outer side of the long arm of one adjacent U and the end of the long arm being connected to the inner side of the long arm of the other adjacent U to form an interlocking structure, a leg pivoted between the arms of each U, outward pivotal movement of each leg being limited by engagement of the central portion of the U with the outer part of

the leg, and means for attaching said member to a table top.

7. A table support as in claim 4, in which the central portion of each **U**, which contacts 5 with the leg when the latter is outwardly extended, is beveled to present a bearing surface substantially parallel to the surface of the leg in contact therewith.

8. A table, comprising a plate, four uniformly angularly spaced angles, each having 10 one flange spot-welded to the upper face of said plate and the other flange extending upwardly therefrom, four angle bars, each arranged with one flange parallel to said plate 15 and the other flange overlapping and spot-welded to the upstanding flange of one of said angles, said overlapping flanges being arranged to form the four walls of a square chamber at the center of the plate, a square 20 internally threaded member in said chamber, a table support adapted to engage the underside of said plate and having a second threaded member for engagement with the first threaded member, and a table top resting upon and secured to the flanges of the 25 angle bars parallel to said plate.

9. A table, comprising a table top, a support therefor, a nut and bolt type connection 30 between said top and support, a plurality of legs pivotally connected to said support, the upper ends of said legs projecting above the top of said support when the legs are drawn together, whereby the tightening of said bolt and nut connection causes the table top to 35 engage the upper ends of the legs and hold the latter in outwardly splayed, table-supporting position.

10. A table as in claim 9, in which the upper ends of the legs are cut at an angle 40 such that when the legs are in outwardly splayed position the top surfaces thereof are substantially parallel to the under surface of the table top and substantially flush with the top surface of the support.

45 11. A table support, comprising a member in the form of a hollow cross with a central square chamber and four rectangular pockets extending radially from the four sides of the central chamber but separated therefrom by 50 vertical partitions, a leg having one end pivotally mounted in each rectangular pocket.

12. A table support, as in claim 11, in which the means for attaching the member to the table top comprises a nut and bolt, 55 one of which is formed with non-circular sides for non-rotatable engagement with the walls of the central chamber.

13. A table, comprising a table top, a support therefor, a boss on the support adapted 60 to enter a recess in the underside of the table top to hold the latter in concentric position with respect to the support, interengaging portions on the table top and the support adapted to be brought into and out of engagement by rotation of the table top with respect

to the support, and means for locking the top and support in engaged position.

14. A table, comprising a table top, a support therefor, including a member having at least three pockets disposed radially and symmetrically about the vertical axis of the support, each pocket being formed of sheet metal bent about vertical lines of fold into **U**-form, 70 a leg mounted between the arms of each **U**, a rigid plate secured to the inner face of the central portion of each **U** with its upper end extending above the latter and inwardly flanged, and means for retaining the top and support in rotatable concentric relation, outwardly extending portions on the underside of said top adapted in one angular position 75 of the top with respect to the support to extend under the flanged ends of said plates and thereby connect the top to the support. 80

15. A table as in claim 14, which also comprises means for releasably locking the top and support in said relative angular position. 85

16. A table top, comprising a wooden sheet, a metal plate below the central part of said sheet in parallel spaced relation thereto, a series of metal members extending outwardly from said plate in a generally radial direction, each of said members having a flange parallel to the underside of the wooden sheet and secured thereto, a flange parallel to said metal plate and secured thereto, and an intervening vertical flange or web connecting said parallel flanges, and means for connecting said metal plate and parts connected therewith to a table support. 90

17. A table, comprising a wooden sheet, a metal member having a flat under surface, radiating metallic arms connected to said member and secured to the underside of said sheet, a table support having a flat upper surface adapted to contact with the flat under surface of said member, means for detachably connecting said member and said support, and legs pivotally connected to said support. 105

18. A table as in claim 17, in which the upper ends of the legs project above the flat upper surface of said support when the legs are drawn together whereby the connection of the table top to the support causes the table top to hold the latter in outwardly splayed table-supporting position. 110

In testimony whereof I have hereunto set my hand.
